UNITED STATES PATENT OFFICE.

CLIFFORD A. WOODBURY, OF MEDIA, PENNSYLVANIA, ASSIGNOR TO E. I. DU PONT DE NEMOURS & COMPANY, OF WILMINGTON, DELAWARE, A CORPORATION OF DELAWARE.

BLASTING CAP.

No Drawing.

Application filed February 5, 1924. Serial No. 690,882.

To all whom it may concern:

Be it known that I, CLIFFORD A. WOODBURY, a citizen of the United States, and a resident of Media, in the county of Delaware and State of Pennsylvania, have invented a certain new and useful Blasting Cap, of which the following is a specification.

This invention relates to blasting caps, and, more particularly to blasting caps of the composition type. Such caps, as usually manufactured, comprise a metallic shell containing a base charge and a primer charge pressed on the top of the base charge. Among the explosives used for the base charge have been, for example, trinitrotoluene, tetrantromethylaniline, tetrannitroaniline, and nitrated ivory nut meal. For the primer charge have been used primary detonating compounds such as mercury fulminate, lead azide, cyanurtriazide, and diazodinitrophenol, various oxidizing agents such as potassium chlorate being often mixed with the priming compound. A perforated capsule may be pressed down on the top of the primer charge for the purpose of giving additional confinement to the charge and thereby increasing the efficiency of the detonation. The practice of using a base charge of some explosive less expensive than mercury fulminate, instead of using a charge of fulminate alone, arose as a measure of economy; by the present invention a portion of the enormous stock of propellant explosives on hand in many countries at the close of the war may be economically utilized in base charges.

An object of the present invention is to provide a cap having a charge of great efficiency in the detonation of other explosives, and at the same time to produce an economy in the cost of the explosive materials used in the cap. To this end, and also to improve generally upon caps of the general character indicated, my invention consists in the various matters hereinafter described and claimed.

In brief, my invention comprises the use of finely ground pyro powder as the base charge, meaning by "pyro powder" that grade of smokeless powder made from nitrocellulose almost completely soluble in a mixture of two parts by volume of ether to one part of ethyl alcohol and having a nitrogen content of about 12.60%. Large stocks

of this powder were left on hand at the close of the recent war, and should be utilized. It is not, however, itself a detonating agent, that is, a detonation cannot be set up in relatively small quantities of it by the explosion of an adjacent small charge of mercury fulminate. Now I have discovered that when such pyro powder is finely ground, it becomes a satisfactory material for use as a base charge in a detonator. I have found that to some extent the efficiency of the detonation of the ground pyro powder is dependent on the degree of subdivision. For example, material so ground that everything passes a 30 mesh screen, and with 35% passing a 100 mesh screen makes a rather weak, low velocity base charge, while material so ground that 60% passes a 100 mesh screen makes a very satisfactory base charge. I prefer to use pyro powder so ground that at least 90% passes a 100 mesh screen.

In loading a shell I may, for example, press into the cap shell 6 grains of ground pyro powder, using a pressure of 180 to 200 pounds per square inch, and on top of this, I may press 6 grains of a mixture of 90% mercury fulminate and 10% potassium chlorate with a super-imposed copper capsule using a pressure of about 160 pounds per square inch. A very efficient detonator is thus produced.

It will be understood that I do not confine the invention to the weights of material, the relative proportions of the base and primer charges or the pressures above stated, since, of course, these may be varied widely, depending upon the type of detonator desired. Also any of the known primary detonating agents, with or without the perforated capsule above described may be used. Also, if desired, the ground pyro powder may be mixed with an oxidizing agent such as potassium chlorate. While particular reference has been made to pyro powder, that being the particular smokeless powder of which great quantities are now on hand and whose utilization is, therefore, particularly desirable, it will be understood that the invention is not confined to that particular nitrocellulose smokeless powder.

I claim:

1. A detonator having a charge comprising ground smokeless powder.
2. A detonator having a main charge com-

prising ground smokeless powder, and a primary detonating compound.

3. A detonator having a secondary charge comprising finely ground smokeless powder, and a primary detonating charge of fulminate of mercury.

4. A detonator having a base charge comprising ground pyro powder having a fineness such that all will pass a 30 mesh screen and substantially between 35 and 90% will

pass a 100 mesh screen, and a primary detonating compound.

5. A detonator having a base charge of ground pyro powder having a fineness such that all will pass a 30 mesh screen and at least substantially 90% will pass a 100 mesh screen, and a top charge of fulminate of mercury.

In testimony whereof I affix my signature.

CLIFFORD A. WOODBURY.
